Application April 15, 1948, Serial No. 21,257

8 Claims. (Cl. 29—62)

1

My invention relates in general to an automatic spindle machine capable of rotating and working an elongated and warped workpiece, and in particular to the workpiece supporting and feeding mechanism of the spindle machine.

Many various spindle machines have been constructed in which the workpiece is fed endwise through the spindle or the head of the machine. These machines, however, have never been capable of handling large workpieces which may be warped. The previous spindle-fed automatic machines have been constructed for making bolts or other similar small diameter articles. When the workpiece is small in diameter it is very easy to construct a supporting structure for supporting the part of the workpiece which extends out of the head of the machine. However, when a large diameter workpiece is used the simple supporting structure, which is commonly a ring through which the workpiece extends, is inadequate and soon becomes damaged. I have constructed a supporting structure which will support this workpiece and which will permit the tail end of the workpiece to whip about while it is rotating. My supporting structure has supported a solid workpiece of 12 inches in diameter which was warped from $\frac{1}{16}$ inch to $\frac{3}{32}$ inch in its diameter. It can be easily seen that rotating an elongated workpiece of these dimensions with only one end of the workpiece chucked will cause the tail end to build up tremendous whipping power. After the workpiece has built up a rotational and whipping momentum, it would soon pound to pieces a lead lined sleeve or other similar cushioned support sleeve. I have discovered that it is possible to support this whipping tail end of an elongated workpiece of this size with the structure which is described and claimed herein.

One of the objects of my invention is therefore to provide a single spindle bar machine capable of handling elongated and warped large diameter workpieces.

Another object of my invention is to provide a spindle machine with a chucking collet and a feeding mechanism to feed the workpiece endwise through the spindle and into the chucking collet.

Another object of my invention is to provide a supporting structure in which the workpiece engaging sleeve thereof can move reciprocally towards and away from the chucking collet and thereby move the workpiece endwise into the chucking collet.

Another object of my invention is to provide a

2

bar machine with a supporting structure which will support the whipping tail end of an elongated warped workpiece while it is rotating.

A further object of my invention is to provide a mechanism for rotatably supporting an elongated and warped workpiece in a rotary spindle with a supporting socket carried by supporting track means and disposed in axial alignment with the spindle, and means in this socket to engage the warped workpiece and movable with the whipping movement of the workpiece.

Another object of my invention is to provide a machine having a rotary spindle with a chucking collet and a workpiece support and feed means for feeding the workpiece endwise into the chucking collet with synchronized cam means to open the chucking collet when the workpiece is being fed therein.

Other objects and a fuller understanding of my invention may be had by referring to the following description and claims, taken in conjunction with the accompanying drawing, in which:

Figure 1 of my drawings is a perspective view of a spindle machine showing my workpiece support and feed mechanism;

Figure 2 is a perspective view of the back of this same machine showing the stock stop and various cutting tools;

Figure 3 is an enlarged side-elevational view with certain parts shown in cross section to illustrate the rotary spindle with the chucking collet and the workpiece support and feed mechanism;

Figure 4 is a view along the line 4—4 of Figure 3;

Figure 5 is an enlarged fragmentary view of the workpiece support mechanism showing the position of the bearing unit in the supporting socket while a perfectly straight workpiece is being supported;

Figure 6 is an enlarged exaggerated view the same as Figure 5, illustrating the position of the bearing unit in the supporting socket while supporting a warped workpiece;

Figure 7 is also an enlarged fragmentary view illustrating how the bearing unit may be forced into the supporting socket by a warped workpiece;

Figure 8 is a schematic drawing to better illustrate the operation of the support and feed mechanism in synchronism with the rotary spindle and chucking collet; and

Figure 9 is a cam diagram of the cycle of operation of my machine.

I have designated my single spindle machine

which I have constructed and successfully operated, as having a head structure 10 and a back housing structure 11 mounted on a base 12. The head structure 10 supports a rotary spindle 17 having a chucking collet 27. Cut-off and forming tools 14, which are shown in perspective in Figure 2, are disposed on the sides of the head structure 10 and near the chucking collet 27. In the description of my machine I am not describing these tools, since they in no way affect the operation or construction of my workpiece support and feeding mechanism 13 or its association with the rotary spindle and chucking collet. Therefore, these working tools may be of any suitable design and construction commonly known in the art of automatic machines, and the operation thereof may be controlled by any suitable means. The head structure 10 may be of any suitable housing construction and is designed to rotatably support the rotary spindle which extends therethrough.

I have designated the workpiece support and feed mechanism with the number 13. As is illustrated in Figure 1 of my drawings, this workpiece support and feed mechanism 13, which is supported by the head structure 10 and the back housing structure 11, is operable to support an elongated and warped workpiece while it is being rotated by the rotary spindle 17 disposed within the head structure 10. The workpiece is forwarded endwise through the rotary spindle and into the chucking collet 27 for machining by the tools 14 illustrated in perspective in Figure 2. The workpiece may be said to have a forward end portion which extends through the head of the machine and is engaged by the working tool, and to have a tail end which is supported by the workpiece support and feed mechanism 13.

The head structure 10 of my machine has a front wall 15 and a back wall 16. The front wall 15 is next adjacent the cutting tools 14 which are shown in perspective in Figure 2. The back wall 16 is substantially parallel to the back housing structure 11, and is spaced therefrom. The front wall 15 and the back wall 16 have an aligned opening through which the rotary spindle 17 extends. This rotary spindle, including all of its component parts, is best illustrated in the Figure 3 of the drawings.

To construct this rotary spindle 17 which is illustrated in cross section in Figure 3, I have used a spindle shell 20 which extends through the head structure 10 and is bearinged in the openings in the front wall 15 and the back wall 16. An insert 21 having a cam face 22 on the inside thereof is drivingly fastened in the forward end of the spindle shell 20 by a drive pin 23 or other suitable means. This insert 21 is usually constructed of a hardened steel to resist wearing caused by the operation of the chucking collet. I have found it very advisable to use tapered roller bearing races 24 to rotatably support the spindle shell 20 in the front wall 15 and in the back wall 16 of the head structure 10. The tapered roller bearing races prevent endwise play of the rotary spindle in the head without having any high friction shoulders rubbing against each other. These roller bearing races 24 are a standard roller bearing race unit which will rotatably support the spindle in the head, and at the same time prevent endwise play or movement of the spindle. It is understood that any suitable bearing means may be employed for this purpose.

I have fastened a drive gear 25 to the spindle shell 20 by means of a key which is illustrated

as being disposed between the spindle shell 20 and the drive gear 25. This drive gear 25 may be gearingly connected to the electric motor or other drive means for rotating a rotary spindle 17. In the machine which I have constructed, I place this drive gear on the spindle shell 20 and between the front wall 15 and the back wall 16 of the head structure 10. Thus, the driving of the spindle is completely enclosed by the head structure and is disposed between the tapered roller bearing races 24 which bearingly support the spindle shell 20. A collet 27 having a cam face 28 to engage the cam face 22 of the spindle shell 20 is inserted into the spindle shell 20. This chucking collet 27 is adapted for endwise movement of the spindle shell, and when forced into the spindle shell closes onto a workpiece which is inserted therein. The collet cam face 28 and the cam face 22 on the spindle shell cooperate to radially contract the collet 27 when it is axially moved. I have found it very advisable to provide the collet 27 with pads 29 on the inside surface thereof. These pads 29 may be easily changed, and their dimensions are controlled by the size of the workpiece which is to be machined. For example, for a large diameter workpiece a very thin pad 29 would be used, and for a small diameter workpiece a thick pad 29 would be used.

I have provided the collet 27 with a collet tube 30 threaded thereon and extending through the back wall 16 of the head structure 10. This collet tube 30 interconnects the collet 27 and a spring type chucking mechanism 31 therein, which normally urges the collet tube 30 and the collet 27 therewith endwise for gripping a workpiece inserted in the rotary spindle. The outside diameter of the collet tube 30 is smaller or less than the inside diameter of the spindle shell 20. When a warped elongated workpiece is inserted in the machine, the workpiece is rotated by the collet chuck at the forward end of the machine or next to the pads 29.

In Figure 3 of my drawings, I illustrate a spacing between the feed tube 60 and the collet tube 30. In the actual construction of the machine which I have built, this space need be only a few sixteenths of an inch to permit the feed tube to whip about with the whipping movement of the tail end of the workpiece.

The spring type chucking mechanism 31 which operates the collet 27 to rotate the workpiece, is disposed between the back wall 16 of the head structure 10 and the back housing structure 11. This spring type chucking mechanism 31 has a housing 35 carried by the spindle shell 20. A plurality of chucking springs 36 axially aligned with the spindle shell 20 are carried within this housing 35. A collet tube plate 37 extends about the spindle shell 20 and is movable axially into the housing 35 and against the urging of the chucking springs 36. This collet tube plate 37 may be fastened to the housing 35 by bolts 38 which extend through the chucking springs 36 and the wall of the housing 35 and are threaded into the collet tube plate. The chucking springs 36 urge the collet tube plate 37 axially of the spindle shell 20 and towards the back housing 11. I have further provided the collet tube with a thrust nut 39 which is threaded onto the end of the collet tube. Thrust roller bearings 40 space this thrust nut 39 from the collet tube plate 37.

The thrust nut 39 is fastened to the collet tube plate 37 by bolts 41 whereby the collet tube plate

37 rotates with the thrust nut 39 and the collet tube 30. The chucking springs 36 urge the collet tube plate 37 out of the housing 35 to keep the collet chuck 27 gripping the workpiece held thereby. A thrust ring 42 extends about the thrust nut 39 and is axially movable to compress the chucking springs 36 in the spring type chucking mechanism 31. This thrust ring 42 is pivotally carried by a cradle 43. A chucking cam 44 is provided to actuate and move this chucking cradle 43 to compress the chucking springs and open the chucking collet 27. This chucking cam 44 is carried by a cam shaft 80 and is coordinated with the workpiece support and feed mechanism in such manner that the workpiece will be moved endwise into the chucking collet while the chucking collet is open.

A hand wheel 102 carried by a shaft 103 may be actuated to move the chucking cradle 43. The shaft 103 is carried by the cradle 43 and engages the head structure 10. This hand wheel 102 permits manual operation of the chucking mechanism when the machine is not in operation.

The workpiece support and feed mechanism 13, best illustrated in Figures 1 and 3, is disposed in axial alignment with the rotatable spindle and between the head structure 10 and the back housing structure 11 of my machine. I have provided parallel track members 50 extending between the head structure and the back housing structure to support the workpiece support and feed mechanism 13 for movement towards and away from the head structure rotary spindle. In the machine which I have constructed and which is illustrated in the drawings as the preferred embodiment of my invention, I have used cylindrical or elongated rods for the parallel track members 50. The track members have threads on the ends thereof and may thus be threaded into the head structure 10 and extend through an opening in the back housing structure 11. Lock nuts 51 disposed on each side of the back housing structure 11 prevent loosening of the track members 50.

My workpiece support and feed mechanism 13 generally comprises a roller bearing unit 52 operably socketed in a socket 53. In Figures 5, 6, and 7 I illustrate my roller bearing unit 52 as being constructed from tapered roller bearing races 54 and 55 mounted in a housing 56. This bearing housing 56 has a socket ring or flange 57 extending thereabout and adapted to be seated in the socket 53. The socket ring 57 has a radius surface 58 on one side thereof, and a radius surface 59 on the other side. These radius surfaces 58 and 59 engage the socket 53 and are curved to permit slight wobbling or rocking of the bearing unit 52 in the socket 53. I have fastened a feed tube 60 to the inside of the roller bearing unit 52 and to the housing thereof, 56. This feed tube 60 extends through the spring type chucking mechanism 31 and into the collet tube 30 terminating at the chucking collet 27. The feed tube 60 is slidably axially relative to the collet tube and the chucking collet to feed the workpiece endwise into the chucking collet.

I have found it preferable to provide this feed tube 60 with a workpiece pad 61 (see Figure 3) which engages the workpiece. By using these workpiece pads 61 inside the feed tube 60 I do not have to have a feed tube for each diameter workpiece which will be run through the machine. If a small diameter workpiece is to be machined the pad 61 is replaced by a larger pad which will grip the smaller workpiece. The feed tube 60 and the 75

roller bearing races 54 rotate with the workpiece and thus with the chucking collet 27.

The socket 53, illustrated in Figure 5, which supports the roller bearing unit or feed slide 52, is constructed from a socket housing 65 and a socket cap 66. The socket housing 65 defines a socket surface 67 on the inside thereof to engage the radius surface 58 on the socket ring 57. The socket cap 66 is bolted to the socket housing 65, and thus forms the other side of the socket. I have inserted a ring 68 in the socket housing 65 and have provided this ring 68 with a socket surface 69 to engage the radius surface 59 of the socket ring 57 on the feed slide or roller bearing unit 52. The ring 68 is slidable in the housing 65 towards and away from the socket surface 67. Pressure springs 70 are mounted in aligned recesses in the socket cap 66 and the ring 68 to urge the ring 68 towards the socket surface 67 of the socket housing 65.

The socket housing 65 illustrated in Figure 3 is carried by a truck 72 which rolls on the parallel track members 50. The truck 72 has top truck wheels 73 which rest on the track members 50, and has bottom truck wheels 74 which are carried along underneath the track members 50. These top and bottom truck wheels 73 and 74 on the truck 72 movably support the workpiece support and feed mechanism 13 for movement along the track members 50 towards and away from the head structure 10 of the machine. When the workpiece support feed mechanism 13 is moved towards the head structure 10 a workpiece supported thereby is moved endwise into the chucking collet 27 by the feed tube 60 which extends into the rotary spindle. When the workpiece support and feed mechanism 13 is moved away from the head structure 10 and towards the back housing structure 11, the feed tube 60 slides over the workpiece which is held by the chucking collet 27.

In Figure 5 of my drawings I illustrate the position of the component parts of the workpiece support and feed mechanism 13 when the workpiece is true and is not warped or out of alignment. In observing the drawing it is noted the roller bearing unit 52 is alignably seated in the socket 53. However, when a warped workpiece is put into the machine the bearing unit 52 must be allowed to whip or move with the workpiece. In Figures 6 and 7 I illustrate positions of the bearing unit in the sockets in exaggerated whipping position. Even though the workpiece is whipping, and thus the bearing unit 52 is carried about thereby, it is still supported by the socket 53. The ring 68 and the pressure spring 70 in the socket 53 always maintains a contact between the bearing ring 57 and the inner surfaces of the socket housing 65. I have discovered that by using this roller bearing unit so that the feed slide rotates with the workpiece and by using the socket 53 to support the roller bearing unit, the workpiece is allowed to whip while it is rotating and yet does not build up tremendous whipping forces which would damage machines. The workpiece also does not have a chance to build up a force before it engages the socket; thus a very large and heavy workpiece may be supported.

As is illustrated in Figure 3, a spring abutment member 76 is fastened to the back housing structure 11 and encloses the end of the spring tube 75 which extends beyond the back housing structure. A feed slide spring 77 is operably carried by this spring tube 75 and abuts the

spring abutment member 16 and the truck 12 to urge the truck 12 and the feeding mechanism therewith towards the chucking collet. The spring 71 has a strength great enough to expand lengthwise to feed the workpiece endwise into the chucking collet. I have provided a cam mechanism associated with the truck 12 to compress the spring and thereby move the feed slide mechanism away from the chucking collet in readiness to move the workpiece endwise into the chucking collet. This cam mechanism comprises a feed cam 78 and a feed cam roller 79 engaging the feed cam 78. The feed cam 78 is carried by a suitable cam shaft 80 extending from the head 10 towards the back housing structure 11. The cam shaft 80 may be rotated by any suitable means, and, as is shown in the working diagram of Figure 8, is synchronously connected with the operation of the working tools and chuck collet. The feed cam roller 79 is rotatably carried by the truck 12 and engages the feed cam 78. When the feed cam 78 is rotated the truck 12 is moved on the track 50 towards the back housing 11 and away from the collet.

In Figure 8 of my drawing I illustrate symbolically my workpiece support and feeding mechanism including the stock stop and the chucking collet. In this drawing, I diagrammatically illustrate the rotary spindle 17, which has the drive gear 25, rotated through a pinion gear 95 by a suitable driving unit 96. The driving unit 96 is symbolically illustrated as being connected to the pinion gear 95 by dash-dot lines 97. A second pinion gear 98 also engaging the driving gear 25 drives the cam shaft 80 through suitable gearing and drive means illustrated by the dash-dot lines and the gear box 99. The stock stop 84 is also illustrated as being operated through a rack and gear mechanism 85 controlled by a stock stop cam 86 which is carried by the cam shaft 80. The workpiece feeding mechanism 13 is illustrated as being symbolically connected and operated by the feed cam 78 by means of dash-dot line 100, and the chucking mechanism 31 is symbolically connected to the chucking cam 44 by the dash-dot line 101.

The complete operation of the machine may be easily followed by referring to the Figure 9 which is a cam diagram of the stock stop chucking and the workpiece feeding mechanism. The complete cycle of operation of the machine occurs during one rotation of the cam shaft 80, and thus one rotation of each of the cams 44, 78, and 86. Following through the cam diagram in Figure 9, it is illustrated that when the machine is in operation the stock stop is first lowered to engage the workpiece when it is moved endwise into the chucking collet. While the stock stop is in this lowered position, the chucking collet is opening to release the workpiece to permit the workpiece to be moved endwise and against the stock stop 84. The cam 78 moves the workpiece support and feed mechanism along the track 50 towards the back housing 11 in readiness for moving the workpiece forward into the chucking collet. Further rotation of the cam shaft 80 permits the feed spring 71 to expand, thus moving the workpiece feeding mechanism towards the head 10 to move the workpiece into the chucking collet and against the feed or stock stop 84. After the workpiece has been moved endwise the chucking cam 44 permits the chucking collet to close on the workpiece, and the stock stop cam 86 raises the stock stop 84 so that the

workpiece may be machined. After the workpiece has been machined and the finished product cut from the end thereof, this complete cycle of again moving the workpiece endwise is repeated. The whole cycle including the machining and the chucking of the workpiece may thus be a continuous and automatic cycle.

Although the invention has been described with a certain degree of particularity in its preferred form, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. In a mechanism for rotatably supporting an elongated workpiece, a rotary spindle having a collet tube with a collet, track means extending longitudinally from the spindle, a socket carried by the track means and disposed in axial alignment with the spindle for reciprocal movement toward and away from the collet, said socket having opposed inner bearing surface means, a ring having outer contact surface means rockably fitting between said opposed inner bearing surface means of said socket, a feed tube connected to and supported by said ring in axial alignment with the spindle, said feed tube being within the collet tube and spaced therefrom and receiving and supporting the workpiece in substantial alignment with the collet and having means to grip the workpiece to move the same longitudinally into the collet upon longitudinal movement of the socket and ring toward the collet, said opposed inner bearing surface means of said socket comprising first and second inner bearing surfaces divergently disposed with respect to each other, said outer contact surface means of said ring comprising first and second outer contacting surfaces convergently disposed with respect to each other and fitting respectively against said first and second inner bearing surfaces of said socket, said second inner bearing surface being longitudinally movably mounted with respect to said first inner bearing surface, said ring being laterally and rockably movable in said socket and permitting whipping movements of said feed tube and the workpiece therein upon longitudinal movement of said second inner bearing surface with respect to the first inner bearing surface, and resilient means urging said second inner bearing surface longitudinally toward said first inner bearing surface and thereby resiliently and rockably supporting said ring within said socket to permit said whipping movements of the feed tube and the workpiece therein.
2. In a mechanism for rotatably supporting an elongated workpiece, a rotary spindle having a collet tube with a collet, track means extending longitudinally from the spindle, a socket carried by the track means and disposed in axial alignment with the spindle for reciprocal movement toward and away from the collet, said socket having opposed inner bearing surface means, a ring having outer contact surface means rockably fitting between said opposed inner bearing surface means of said socket, a feed tube connected to and supported by said ring in axial alignment with the spindle, said feed tube being within the collet tube and spaced therefrom and receiving and supporting the workpiece in substantial alignment with the collet and having means to grip the

workpiece to move the same longitudinally into the collet upon longitudinal movement of the socket and ring toward the collet, said opposed inner bearing surface means of said socket comprising first and second inner bearing surfaces divergently disposed with respect to each other, said outer contact surface means of said ring comprising first and second outer contacting surfaces convergently disposed with respect to each other and fitting respectively against said first and second inner bearing surfaces of said socket, said second inner bearing surface being longitudinally movably mounted with respect to said first inner bearing surface, said ring being laterally and rockably movable in said socket and permitting whipping movements of said feed tube and the workpiece therein upon longitudinal movement of said second inner bearing surface with respect to the first inner bearing surface, resilient means urging said second inner bearing surface longitudinally toward said first inner bearing surface and thereby resiliently and rockably supporting said ring within said socket to permit said whipping movements of the feed tube and the workpiece therein, and spring feed means engaging the socket to move the same including the ring and the feed tube therewith along the track means towards the collet to feed the workpiece endwise through the spindle and into the collet.

3. In a mechanism for rotatably supporting an elongated workpiece, a rotary spindle having a collet tube with a collet, track means extending longitudinally from the spindle, a socket carried by the track means and disposed in axial alignment with the spindle for reciprocal movement toward and away from the collet, said socket having opposed inner bearing surface means, a ring having outer contact surface means rockably fitting between said opposed inner bearing surface means of said socket, a feed tube connected to and supported by said ring in axial alignment with the spindle, said feed tube being within said collet tube and spaced therefrom and receiving and supporting the workpiece in substantial alignment with the collet and having means to grip the workpiece to move the same longitudinally into the collet upon longitudinal movement of the socket and ring toward the collet, said opposed inner bearing surface means of said socket comprising first and second inner bearing surfaces divergently disposed with respect to each other, said outer contact surface means of said ring comprising first and second outer contacting surfaces convergently disposed with respect to each other and fitting respectively against said first and second inner bearing surfaces of said socket, said second inner bearing surface being longitudinally movably mounted with respect to said first inner bearing surface, said ring being laterally and rockably movable in said socket and permitting whipping movements of said feed tube and the workpiece therein upon longitudinal movement of said second inner bearing surface with respect to the first inner bearing surface, resilient means urging said second inner bearing surface longitudinally toward said first inner bearing surface and thereby resiliently and rockably supporting said ring within said socket to permit said whipping movements of the feed tube and the workpiece therein, spring feed means engaging the socket to move the same including the ring and the feed tube therewith along the track means towards the collet to feed the workpiece endwise through the spindle and into the collet.

collet, and cam means operably associated with the socket to compress the spring feed means and thereby move the said socket including the ring and the feed tube therewith along the track means away from the collet in readiness for another feeding movement.

4. In a mechanism for rotatably supporting an elongated workpiece, a rotary spindle having a collet tube with a collet, track means extending longitudinally from the spindle, a socket carried by the track means and disposed in axial alignment with the spindle for reciprocal movement toward and away from the collet, said socket having opposed inner bearing surface means, a ring having outer contact surface means rockably fitting between said opposed inner bearing surface means of said socket, a feed tube bearingly connected to and supported by said ring in axial alignment with the spindle, said feed tube being within said collet tube and spaced therefrom and receiving and supporting the workpiece in substantial alignment with the collet and having means to grip the workpiece to move the same longitudinally into the collet upon longitudinal movement of the socket and ring toward the collet, said opposed inner bearing surface means of said socket comprising first and second inner bearing surfaces divergently disposed with respect to each other, said outer contact surface means of said ring comprising first and second outer contacting surfaces convergently disposed with respect to each other and fitting respectively against said first and second inner bearing surfaces of said socket, said second inner bearing surface being longitudinally movably mounted with respect to said first inner bearing surface, said ring being laterally and rockably movable in said socket and permitting whipping movements of said feed tube and the workpiece therein upon longitudinal movement of said second inner bearing surface with respect to the first inner bearing surface, and resilient means urging said second inner bearing surface longitudinally toward said first inner bearing surface and thereby resiliently and rockably supporting said ring within said socket to permit said whipping movements of the feed tube and the workpiece therein.

5. In a machine for rotatably supporting an elongated and warped workpiece, the provision of, a housing, a collet tube journaled in said housing, a feed tube co-axially aligned with and spaced from said collet tube, tracks on said housing extending longitudinally of said feed tube, and socket and ring means movable as a unit on said tracks and bearingly and resiliently supporting said feed tube for reciprocal movement longitudinally of said collet tube, said socket means having first and second opposed bearing surfaces between which said ring means fits, said second bearing surface being movable toward and away from said first bearing surface and providing variable distances between said opposed bearing surfaces, resilient means urging said second bearing surface toward said first bearing surface, said ring means rockably fitting between said opposed bearing surface and accommodating axial mis-alignment between said feed tube and said collet tube.

6. In a machine for rotatably supporting an elongated and warped workpiece, the provision of, a housing, a collet tube journaled in said housing, a feed tube co-axially extending within and spaced from said collet tube, tracks on said housing extending longitudinally of said feed

tube, and resilient, self-aligning bearing means reciprocally movable on said tracks and bearingly and rockably supporting said feed tube, said bearing means comprising socket and ring means, said socket means having first and second opposed bearing surfaces between which said ring means fits, said second bearing surface being movable toward and away from said first bearing surface and providing variable distances between said opposed bearing surfaces, resilient means urging said second bearing surface toward said first bearing surface, said ring means rockably fitting between said opposed bearing surface and accommodating axial mis-alignment between said feed tube and said collet tube.

7. In a machine for rotatably supporting an elongated and warped workpiece, the provision of, a housing, tracks on said housing, a collet tube journaled in said housing in parallel alignment with said tracks, a truck movable on said tracks, a socket comprising a housing and a cap carried by said truck, a socket ring mounted between said socket housing and said cap, pressure spring means cooperating with said cap and pressing same against said socket ring to resiliently hold the same in said socket housing, and a bearing unit rotatably bearinged in said socket ring, a feed tube carried by said bearing unit, said feed tube extending within and spaced from said collet tube whereby one end of a warped workpiece inserted in the machine is carried by the collet tube and the other end is carried by the feed tube, said socket ring rockably fitting between said socket housing and said cap and accommodating axial mis-alignment between said feed tube and said collet tube.

8. In a machine for rotatably supporting an elongated workpiece, the provision of, a housing, tracks on said housing, a collet tube journaled in said housing in parallel alignment with said tracks, a truck movable on said tracks, a socket carried by said truck, said socket having opposed inner bearing surface means, a ring hav-

ing outer contact surface means rockably fitting between said opposed inner bearing surface means of said socket, a bearing unit rotatably bearinged in said ring, a feed tube carried by said bearing unit, said feed tube extending within and spaced from said collet tube whereby one end of a workpiece inserted in the machine is carried by the collet tube and the other end is carried by the feed tube, said opposed inner bearing surface means of said socket comprising first and second inner bearing surfaces divergently disposed with respect to each other, said outer contact surface means of said ring comprising first and second outer contacting surfaces convergingly disposed with respect to each other and fitting respectively against said first and second inner bearing surfaces of said socket, said second inner bearing surface being longitudinally movably mounted with respect to said first inner bearing surface, said ring being laterally and rockably movable in said socket and permitting whipping movements of said feed tube and the workpiece therein upon longitudinal movement of said second inner bearing surface with respect to the first inner bearing surface, and resilient means urging said second inner bearing surface longitudinally toward said first inner bearing surface and thereby resiliently and rockably supporting said ring within said socket to permit said whipping movements of the feed tube and the workpiece therein.

ALFRED E. DRISSNER.
